UNITED STATES PATENT OFFICE.

OTTO F. GRAEBNER, OF TOLEDO, OHIO, ASSIGNEE TO THE WILLYS-OVERLAND COMPANY, OF TOLEDO, OHIO, A CORPORATION OF OHIO.

MEANS FOR SECURING FINISH TO METAL BODIES.

Application filed June 15, 1918. Serial No. 240,260.

To all whom it may concern:

Be it known that I, OTTO F. GRAEBNER, a citizen of the United States, residing at Toledo, in the county of Lucas and State of Ohio, have invented certain new and useful Improvements in Means for Securing Finish to Metal Bodies, of which I declare the following to be a full, clear, and exact description.

10 My invention relates to improved means for securing the upholstery or other finish to the metal bodies of automobiles and the like.

15 A further object of the invention is to provide improved means for securing finish of any desired kind to metallic plates by forming integral with the plates retaining members for securing suitable connecting members thereon, serving to clamp the finish 20 upon the plate.

25 A still further object of the invention is to provide a plurality of resilient retaining members struck outwardly from a metallic plate between which a screw or other threaded member may be driven and held for securing upholstery or other suitable finish upon the plate.

30 Further objects, and objects relating to economies of manufacture and details of construction, will definitely appear from the detailed description to follow.

35 I accomplish the objects of my invention by the devices and means described in the following specification. My invention is clearly defined and pointed out in the appended claims.

40 A structure constituting a preferred embodiment of my invention is illustrated in the accompanying drawings, forming a part of this specification, in which:

Fig. I is a longitudinal, sectional elevation through an automobile body showing the application of the upholstery or other interior finish thereto.

45 Fig. II is an enlarged, detail, sectional view taken on line II-II of Fig. I.

Fig. III is a detail perspective view showing the application of the finish holding screws to the retaining members struck outwardly from one side of a plate comprising a portion of the lining of the body of the automobile.

50 Fig. IV is a detail view illustrating the manner of forming the cuts in the plate

previous to pressing outwardly the sections of material lying between the cuts, and,

Fig. V is a detail perspective view of a slightly modified application of the screw over that shown in Fig. III.

Referring to the drawings, 10 represents the body of an automobile and 11 and 12 the front and rear side doors respectively thereof. A panel 13 is shown in front of the door 11 and the upper and lower panels 14 at the rear of the door 12. On the lower portion of the back of the front seat is also shown a panel or skirting 15. These panels, together with the doors, comprise the principal part of the interior side finish of the body of the car and the material to which the finish or upholstery is applied preferably comprises a plurality of metal plates forming the inner walls of the car body.

Heretofore, it has been customary in using metal plates forming the interior walls or lining of the car to place wooden strips on the back side of the plates for holding the screws serving to retain the upholstery in proper position upon the plates. In the present invention this is obviated and the screws, instead of being applied in the usual manner, are driven into position by the use of a hammer or other tool, thereby greatly reducing the time required for applying the finish to the body of the car and consequently its cost of application as will be readily understood.

The interior finish which is applied to the doors and other parts forming the side walls of the car is preferably composed of three layers of material, as indicated at 16, 17, and 18 in Fig. II, the outer layers being preferably formed of a suitable cloth or fabric and the intermediate layer of stiffening material, such as cardboard or the like.

The metallic plates 19 forming the inner walls of the car body, including the doors and seat back, are provided at suitable intervals with the outwardly struck tongues or retaining members 20 extending in a direction away from the material to be applied to the plate, said tongues forming suitable anchors for holding the screws or bolts 21 or other suitable holding members having abutments to engage the tongues when driven between said retaining members, as shown in Fig. III.

The screw-engaging edges of the tongues

are preferably circular in shape, as indicated at 22, to conform generally to the contour of the screw at the base of the threads though they need not necessarily be cut in this particular manner.

Since the body lining 19 is usually constructed of sheet iron or steel plates, the screw-engaging retaining members 20 when struck outwardly, as indicated in Figs. II 10 and III, are yieldable or spring-like by reason of the resiliency of the metal and when the screw is driven between these members they will be expanded and will spring into the recesses formed between the threads of 15 the screw and grip the latter to hold the same in the desired position.

Any desired number of the screw retaining members may be provided for each screw but in the preferred embodiment I have 20 shown four, while in the modification only two. It will be understood that the screws may be removed when desired by turning them with a screw driver or other suitable tool.

25 These members may be formed by providing the apertures 23 in the plates 19 and preferably, at the same time and with the same tool, producing the radially extending cuts 24 and then striking outwardly 30 from the plate the desired number of the retaining members, as indicated in Figs. III and V. In Figure V, the material intermediate alternate retaining members 20 is cut off more than the other retaining members 35 so that the alternate members may clear the screw 21 and lie flush with the sheet metal.

I am aware that the particular embodiment of my invention, which I have here 40 shown and described, is susceptible of considerable variation, and, therefore, I do not limit the invention to the specific use of applying finish to an automobile body. It will be understood that the invention comprehends the use of any suitable holding member other than a screw which may be driven between the tongues of the plate to be held by the same.

Having thus described my invention, what

I claim as new and desire to secure by Letters Patent, is:

1. In a device for securing separable members together, a metallic plate having a plurality of tongues radiating from a common center, a threaded holding member of uniform cross section throughout its length driven between said tongues and held thereby, and a member held by said holding member.

2. In a device for securing separable members together, a metallic plate having a plurality of outwardly struck tongues, a threaded holding member of uniform cross section throughout its length driven between said tongues and held thereby, and a member 65 connected with said plate by means of said holding member.

3. In a device for securing separable members together, a metallic plate having a plurality of outwardly struck tongues, a plurality of tongues lying flush with the said plate a threaded holding member driven between said tongues and held by said outwardly struck tongues, and a member connected with said plate by means of said holding member.

4. In a device for securing separable members together, a metallic plate having a plurality of outwardly struck tongues, a plurality of tongues lying flush with the said 70 plate, the said last mentioned tongues being shorter than the other tongues, a threaded holding member driven between said tongues and held by said outwardly struck tongues, and a member connected with said plate by means of said holding member.

5. In a device for securing separable members together, a metallic plate having a plurality of outwardly struck tongues, a plurality of shorter tongues lying flush with the plate, all of said tongues, having their free ends notched, and a threaded holding member driven between said tongues and held by said outwardly struck tongues.

In testimony whereof, I affix my signature.

OTTO F. GRAEBNER.
